ELECTRIC LIGHT BULB

Jack N. McCarthy, Meadowood Road,
Tolland, Conn. 06084

Filed Oct. 4, 1971, Ser. No. 186,575

Term of patent 14 years

Int. Cl. D26—04

U.S. Cl. D26—8

FIG. 2

FIG. 1

FIG. 3

FIG. 1 is an elevational view of an electric light bulb showing my new design.

FIG. 2 is a top view thereof.

FIG. 3 is a bottom view thereof.

The characteristic feature of my design resides in the specific configuration of the tapered lamp envelope which is formed as a screw thread.

I claim:

The ornamental design for an electric light bulb, as shown and described.
